GEORGE F. BLAKE, OF BOSTON, MASSACHUSETTS.

Letters Patent No. 101,217, dated March 29, 1870.

MODE OF CUSHIONING STEAM-PISTONS.

The Schedule referred to in these Letters Patent and making part of the same.

To all whom it may concern:

Be it known that I, GEORGE F. BLAKE, of the city of Boston, in the State of Massachusetts, have invented a new and useful Cushioning Steam-Piston, applicable to drilling-machines and other percussive machinery; and I do hereby declare the following to be a full and correct description of the same, reference being had to the accompanying drawings, in which—

Figure 1 is a longitudinal central section of a steam-cylinder with my improved cushioning piston applied.

The object of this invention is to obtain from a steam-piston a powerful stroke, free from shock or jar, by providing a gradual and effectual cushion for the piston, which, while relieving the shock, shall by its elastic impulse increase the effective force of the blow.

The invention consists of a hollow piston placed in a steam-cylinder and provided with a solid piston and with devices for cushioning said solid piston on confined steam at both ends of its stroke, all as herein-after more particularly set forth.

To enable others to make and use my cushioning piston, I will proceed to describe its construction and operation.

The steam-cylinder, marked A¹ A² in the drawing, is of ordinary construction, and takes steam and exhausts in the usual way. In this cylinder is placed the hollow piston B, having the heads H I bolted to it, as shown. In this piston B works the solid piston C on the end of piston-rod F, which passes through head H and out through head P of the main cylinder.

In the head H is port J, covered on the inside by the spring-valve K and the port L, which is open except when the piston C comes over its inner opening at the latter part of its stroke.

In the head I is port E, covered on the inside by spring-valve D and port M, which is open except when the piston C comes over its inner opening at the latter part of its upper or forward stroke.

To the head I is attached the main piston-rod G, which passes through the head N of the steam-cylinder.

Pins o p, placed, respectively, in the heads H and I of piston B, limit in either direction the stroke of piston C, preventing it from passing entirely over ports L and M, thereby regulating the exhaust from hollow piston B.

The drill or hammer to be operated is attached to the end of piston-rod F.

The steam-cylinder is represented in the drawing in a horizontal position, but it may be vertical or at any desired angle.

The operation is as follows:

Steam being admitted into the cylinder at the end

A¹, drives piston B to the other end of the cylinder. At the same time, lifting valve K, it passes through port J into the interior of piston B, and drives piston C to the forward or upper part of that cylinder, exhausting through port M.

On the reverse stroke the cylinder takes steam at the end A², and drives the piston B to the opposite end. At the same time the steam, lifting valve D, enters the piston B through port E, and drives piston C to the lower or rear end of the piston B, exhausting through port L.

It is at the end of the rearward or downward stroke of the piston that the blow of the drill, hammer, or other percussive tool attached to piston-rod F, is given.

At the moment when the blow takes place the piston C is cushioned on compressed steam in the forward end of piston B. This steam gradually exhausts through port M until the piston C comes over that port and closes it, when further exhaust is arrested, and the piston cushions on steam compressed and confined in the space between port M and the forward cylinder-head I, thus giving the full pressure of the area of the steam-cylinder upon the rod F, at the end of its stroke, and greatly increasing by the elastic reaction the effectiveness of the blow.

The rods o p limit the endward motion of the piston C, preventing it from passing entirely over and uncovering ports L and M, thereby regulating the exhaust from cylinder B, by keeping those ports, respectively, closed when steam is entering at the opposite end of piston B.

Having thus fully described my invention,

What I claim, and desire to secure by Letters Patent, is—

1. The hollow piston B, constructed as described, and working inside a steam-cylinder, as set forth.
2. The combination and arrangement of the piston B and piston C in the manner specified.
3. The ports E J, valves D K, and ports L M, arranged for conjoint operation with the pistons B and C, in the manner set forth.
4. A steam-drill, hammer, or percussive engine, in which shock or jar is relieved or prevented by cushioning the impelling piston, first on steam gradually compressed while escaping, and then on steam entirely confined, all in the manner described.

The above specification of my said invention signed and witnessed at Boston this 16th day of September, A. D. 1869.

GEO. F. BLAKE.
